UNITED STATES PATENT OFFICE.

JAMES CARRUTHERS, OF NEW YORK, N. Y.

ADJUSTING APPARATUS.

1,053,157.

Specification of Letters Patent. Patented Feb. 18, 1913.

Application filed July 1, 1910. Serial No. 569,957.

To all whom it may concern:

Be it known that I, JAMES CARRUTHERS, a subject of the King of England, residing at New York city, in the county of New York and State of New York, have invented certain new and useful Improvements in Adjusting Apparatus, of which the following is a specification, reference being had therein to the accompanying drawing.

10 My invention relates to improvements in adjusting apparatus and has particular reference to and is illustrated in the accompanying drawings in its application to an automatic player piano.

15 Referring now particularly to the accompanying drawings, I have illustrated in Figure 1 in vertical elevation with parts broken away, an application of my invention. Fig. 2 is an enlarged view of the 20 tracker board and Fig. 3 a view of the front side of the same, and Fig. 4 is an enlarged section of part of the tracker board shown at the right in Fig. 3.

5 is part of the casing or framework upon 25 which the usual pneumatic 6—9 is mounted and 7 is a central partition of the pneumatic from which air is exhausted by the tube 8. The tubes 10 and 11 connect with either side of the pneumatic as shown and 30 also connect with one of the principal parts of this invention as illustrated on an enlarged scale in Fig. 4.

12 is the sheet of perforated music mounted upon the spools 13 and 14 in the usual 35 manner and 15 is the tracker board attached to the partition 7 of the pneumatic. Should the sheet of perforated music in passing over the tracker board move to the right and thereby not register truly with the perforations in the tracker board, the slide member 16, which under the influence of the 40 spring 20 always bears against the edge of the sheet also moves rightwardly thereby exposing the tube 10 to the atmosphere 45 through the passage 19 allowing the atmosphere to enter the chamber 9 of the pneumatic. The partition 7 is thereby caused to move rightwardly causing the tracker board to assume the position which allows for the 50 proper registration of its openings with the perforations in the sheet music. Should the sheet of music move leftwardly, the slide member 16 under tension of the spring 20, follows the same thereby exposing the tube

11 to the atmosphere which enters by the 55 passage 19 with the result that the partition 7 is moved leftwardly causing the tracker board to move correspondingly thereby re-establishing registration between the perforations in the sheet music and the ports of 60 the tracker board. By this arrangement it will be readily observed that proper registration can be insured automatically without injury to the sheet music. 21 is another spring suitably secured to the block 22 and 65 is adapted to hold the slide 16 upon its seating.

23 is a small lever within convenient reach by which the pinion 24 can be rotated which in turn engages the rack 25 and enables the 70 tracker board to be shifted when required.

Of course it will be understood that various modifications may be made without departing from the spirit of the invention as set forth in the claims.

Having described my invention, what I claim as new, and desire to secure by Letters Patent, is:

1. In piano player mechanism, a tracker bar having note ducts, said tracker bar being adapted for use in combination with sheet music having perforations adapted to register with said note ducts, ports in said tracker bar connected with a pneumatic, a single edge guide in contact with one edge 85 only of said sheet covering said ports, means to keep said guide in contact with the edge of said sheet, said guide having a cut away portion adapted to expose one of said ports to the atmosphere when said sheet shifts in 90 one direction and adapted to expose the other of said ports to the atmosphere when said sheet shifts in the other direction, and a connection between said bar and said pneumatic whereby the former is shifted by the 95 latter whenever said sheet shifts thereby restoring registration between the perforations in said sheet and the ducts in said bar.

2. In an apparatus of the class described, a pneumatic, a tracker over which a perforated sheet of music is adapted to pass, passage-ways through said tracker terminating in ports, a reciprocating slide valve mounted for sliding movement longitudinally of said tracker for opening and closing said 100 ports, guide-ways for said slide valve and resilient means for maintaining the seating of said slide valve, means for maintaining

contact between said slide valve and the edge of said sheet, said slide valve in the normal position of said sheet being in position to close said ports, and said ports being opened by said slide valve by the transverse divergence of said sheet from its normal position, connections between said passage-ways and said pneumatic, and means for adjusting the

relation between said sheet and said tracker when the slide valve is actuated.

In testimony whereof I affix my signature in presence of two witnesses.

JAMES CARRUTHERS.
